UNITED STATES PATENT OFFICE

163,429

SPECTACLE FRONT

Harry Weissman, New Hyde Park, N. Y.

Application January 18, 1951, Serial No. 13,865

Term of patent 14 years

(Cl. D57—1)

To all whom it may concern:

Be it known that I, Harry Weissman, a citizen of the United States and resident of New Hyde Park in the county of Nassau and State of New York, have invented a new, original, and ornamental Design for a Spectacle Front, of which the following is a specification, reference being had to the accompanying drawing, forming a part thereof.

Fig. 1 is a top plan view of a spectacle front, showing my new design.

Fig. 2 is a front elevational view of the spectacle front.

Fig. 3 is a front elevational view on an enlarged scale of half of the design.

Fig. 4 is a fragmentary vertical sectional view of the spectacle front taken on the line 4—4 of Fig. 1.

The essential features of my design reside in the parts shown in full lines, the broken lines showing a complete spectacle front in Figs. 1 and 2 being for illustrative purposes only.

I claim:

The ornamental design for a spectacle front, substantially as shown and described.

HARRY WEISSMAN.
